UNITED STATES PATENT OFFICE.

PHILIP S. MITTS AND WILLIAM J. WINSTON, OF SAGINAW, MICHIGAN, ASSIGNORS TO
MITTS & MERRILL, OF SAGINAW, MICHIGAN, A CORPORATION OF MICHIGAN.

ADJUSTABLE MOUNTING FOR STATIONARY KNIVES OF CUTTING MACHINES.

Application filed January 9, 1922. Serial No. 527,948.

To all whom it may concern:

Be it known that we, PHILIP S. MITTS and WILLIAM J. WINSTON, citizens of the United States, both residing at Saginaw, in the county of Saginaw and State of Michigan, have invented certain new and useful Improvements in Adjustable Mountings for Stationary Knives of Cutting Machines; and we do hereby declare the following to be 10 a full, clear, and exact description of the invention, such as will enable others skilled in the art to which it appertains to make and use the same.

This invention relates to an improved adjustable mounting for the stationary knives of cutting and shredding machines, and pertains more particularly to a knife adjustment for cutting machines of the kind which comprises a casing having a cylindrical drum revolvable within the casing and cutters or knives arranged around the periphery of the drum and carried thereby. Such cutting machines also usually have stationary or anvil knives mounted in the casing and arranged in parallel relation to the drum rim and spaced apart around the lower periphery of the drum.

Cutting machines of this type usually have the casing provided with an inlet hopper at one side of the drum axis and an outlet spout at the other side.

In operation, material to be shredded or cut into granular form is fed into the inlet hopper, and under the combined action of the rapidly revolving drum and of the successive stationary knives, the material is cut and recut while passing from the inlet hopper to the outlet spout, whence it is discharged as granulated or shredded material.

In cutting machines of the character above described it is essential for accurate and uniform cutting that the stationary knives be maintained in proper adjusted relation to the cutting edges of the knives on the revolving drum; that is to say, there must be no yield or movement of the stationary knives, and their working edges must be so gauged with relation to the knives on the drum that the stationary knives can be restored to their proper cutting position after having been taken out for sharpening or dressing without danger of disturbing the proper alignment of the cutting edges of the stationary knives with respect to the cutting edges of the revolving knives. Further-

more, it is essential that proper adjusting and clamping means shall be provided for the stationary knives, to prevent movement or chattering, and it is also desirable that the arrangement of the stationary knives with respect to the casing shall be such that the knives can be easily and quickly removed from the casing, dressed or repaired and replaced in the casing with a minimum of labor and without resort to accurate gauging or measuring methods.

In cutting machines of the kind to which our present improvement is particularly intended to be applied, the knives have usually been mounted in the casing, and the casing, or that part of it in which the stationary knives are mounted, has been made removable so as to gain access to the knives for replacement and repair.

Our present improvement has for its object to provide means whereby the knife will be accurately gauged and held with its cutting edge in proper relation to the cutting edges of the revolving drum knives, also to provide means, easily accessible from outside the casing and at the ends thereof, whereby to clamp the stationary knives in their said adjusted positions.

A still further object is to provide a mounting for the stationary knives, comprising endwise clamping devices that rigidly hold the knife against longitudinal movement and yet permit the knife to be easily and quickly removed from the machine, not by a removal of part of the casing as heretofore, but by withdrawing the knife from the end of the casing, the knife being drawn out longitudinally.

With the foregoing and certain other objects in view, which will appear later in the specification, our improvement consists in the devices described and claimed and the equivalents thereof.

In the drawings, Fig. 1 is a front perspective view of a cutting machine embodying our improvement.

Fig. 2 is an enlarged sectional detail on the line 2—2 of Fig. 1, showing the arrangement of clamping and adjusting devices as applied to one end of the stationary knife.

Fig. 3 is a part sectional diagrammatic detail of a knife, showing the sidewise clamping device and the tapered slot in the casing.

In the drawings, 1 indicates the usual cas-

ing with the inlet hopper 2 at one side and the outlet spout 3 at the opposite side. Removably mounted in the casing 1 is a cylindrical drum 4 carrying on its periphery the 5 usual cutting knives 5.

6, 6 designate the stationary knives which extend parallel to the axis of the drum 4 and are spaced around the lower part of the periphery of the drum and casing and between 10 the inlet hopper and the outlet spout 3, as shown in Fig. 1.

To provide quick and accurate adjusting means whereby the stationary cutting edges of the cutting knives 6 may be adjusted in 15 proper relation to the drum knives 5, we provide on the casing 1 a pair of lugs 7, 7, between which is a knife-receiving slot 8, in which the stationary knife 6 is received by being inserted endwise from the side of 20 the machine as previously described. Each of the lugs 7, 7 is tapped to receive an adjusting stop or bolt 10 with a set nut 11 or equivalent locking means, the heads of the 25 adjustable stops 10 adapted to take against the front and rear edges of the knives 6, 6 respectively. The front or cutting edge is gauged by setting the inner adjusting bolts, and the knives are clamped against outward 30 displacement by the outer set of adjusting bolts.

A bar 12 spans the space between the lugs 7, 7, its ends being removably fastened by bolts 13, or otherwise, to the lugs.

In the middle of the length of bar 12 is an 35 adjusting bolt 14 having a set nut 15, the inner end of this adjusting bolt adapted to engage the end of the knife 6, there being one such bolt at each side of the machine. The knife is readily clamped against end- 40 wise movement, and the bolts 14 are locked, by means of the set nuts 15.

Thus, by means of the bolts 10 and 14, the stationary knives can be easily and quickly clamped in their exact adjusted positions 45 with respect to the knives of the drum.

Referring now to Fig. 3, it will be seen that the slot 8 in the side wall of the casing 1 is made considerably wider than the thickness of the knife at that part farthest from 50 the axis of the drum, and that a set bolt 16, threaded through a lug 17 on the casing, is provided to clamp the stationary knife 6 sidewise against the wall 18 of casing 1. The working edge of the knife is backed by the 55 wall 19 of casing 1, to resist the cutting stress, which is applied against the knife in the direction of the arrow. Thus, when the bolt 16 is loosened, the knife is immediately released from walls 18 and 19 ready to drop 60 to the bottom of the slot 8 when the outer

adjusting bolts 10 are loosened, and one of the bars 12 is removed. The knife may then be taken out of the machine, ground or dressed and returned to its correct position without the employment of skilled labor 65 and without the necessity of accurately re-gauging the cutting edge of the knife with respect to the drum knives.

By the means above described we have produced a simple and relatively inexpensive knife-adjusting means for cutting and shredding machines and the like, all of the adjusting parts being external to the machine and conveniently located so as to be accessible without removing part of the cas- 70 ing.

Extremely accurate adjustment can be easily effected without the necessity of taking accurate clearance measurements, be- 75 cause the setting of the inner set of stops 10 determines the working position of the cutting edges of the stationary knives.

The stationary knives can be easily re- 80 moved by simply withdrawing them side- wise from the casing and as easily replaced.

Having thus described our invention, what we claim and desire to secure by Letters Patent is:

1. In a cutting machine including a re- 85 movable cylindrical knife-carrying drum, a casing and stationary knives removably mounted therein, said casing formed with openings in the end walls thereof, the ends of said stationary knives projecting through said openings and outside of said walls, lugs 90 on said walls adjacent said openings, ad- justable stops on said lugs adapted to engage respectively the inner and outer edges of 95 said stationary knives, a bar removably se- cured to said lugs and spanning said open- 100 ings, and an adjustable stop carried by said bar and adapted to abut against the end of said stationary knife.

2. In a cutting machine including a re- 105 movable cylindrical knife-carrying drum, a casing and stationary knives removably mounted therein, said casing formed with openings in the end walls thereof, the ends of said knives projecting through said open- 110 ings and outside of said walls, adjustable stops on said walls adapted to engage the ends and the inner and outer edges of said stationary knives, and a clamping bolt car- 115 ried by said wall and adapted to abut against the side of said stationary knife to force the knife against the wall of said opening.

In testimony whereof, we affix our signa- tures.

PHILIP S. MITTS.
WILLIAM J. WINSTON.
